UNITED STATES PATENT OFFICE.

MAURICE S. ROSENFELD, OF NEW YORK, N. Y., ASSIGNOR, BY MESNE ASSIGNMENTS,
TO JACOB SCHECHTER, OF NEW YORK, N. Y.

TRANSFER-MACHINE.

1,283,315.

Specification of Letters Patent. Patented Oct. 29, 1918.

Application filed May 14, 1915, Serial No. 28,120. Renewed September 18, 1918. Serial No. 254,672.

To all whom it may concern:

Be it known that I, MAURICE S. ROSENFELD, a citizen of the United States, residing in the borough of the Bronx, county of Bronx, city and State of New York, have invented a certain new and useful Transfer-Machine, of which the following is a specification.

My invention relates to mechanism for applying decalcomania transfers to textile fabrics, such as stockings, neckties, or the like articles, to gloves, paper or any other objects. My invention contemplates the use of the ordinary decalcomania of commerce wherein a design such as a trade mark is printed on a thin sheet of material, such as paper, in such a manner that when the printed surface of the paper is moistened in the presence of heat the design is freed from its adherence to the paper and pressure is applied so that it may be transferred to any other suitable surface. The design is of course in negative on the paper and will be positive when transferred. The object of my invention is to produce a machine which will be rapid and economical in operation, which will consist of but few parts, be cheap to construct, and not likely to get out of order.

This and further objects will more fully appear in the following specification and accompanying drawings considered together or separately.

In the drawings,

Figure 1 is a plan view of the machine; Fig. 2 is a side elevation of the same; Fig. 3 is a front elevation of the same; Fig. 4 is a detail sectional view of the moisture box and anvil; and

Fig. 5 is a diagrammatic view showing the cam movements.

In all of the above views, like parts are designated by similar reference characters.

The device consists of an anvil or platform on which the article to which the transfer is to be applied is placed and secured in position. A piece of paper on which a decalcomania has been impressed is now placed with the printed surface in contact with the article, the same is moistened and heated, the heat and moisture will loosen the printed matter from the paper, and on pressure be-

ing applied to the article the printed matter will adhere to the article. When the pressure is removed the paper may be lifted from the article, leaving the design which was printed thereon on the article.

The decalcomania or transfer employed is not claimed herein as it is a well known article of commerce such as is used for placing lettering or other designs on various articles.

The device comprises a main frame 1, and a secondary frame 2 carried upon a table 3. Carried in the secondary frame 2 is a drive shaft 3¹ on which is mounted a pulley 4 which may be driven by means of a belt from a suitable source of power. The pulley is loose on the shaft and is connected to drive the latter through a clutch 5. The clutch is operated by means of an arm 6, said arm is pivoted to a short shaft 7 which extends through the table, and is provided with a lever 8 which extends toward the front of the table so as to be operated by the knee of the operator.

Mounted on the shaft 3¹ is a pinion 9 which meshes with a gear 10 on a cam shaft 11 supported in the frame 2. The shaft 11 carries three cams 12, 13 and 14.

The frame 1 has two forwardly extending arms 15 and 16, and secured in these arms is a vertically arranged stationary shaft 17. On the shaft 17 is journaled a frame 18. This frame is of open triangular form, and its lower arm is provided with a flat coil 18^a of high resistance wire for a purpose to be hereinafter described. The frame is rotatably mounted on the shaft so as to be swung over the transfer to heat the same.

Carried on the shaft 17 is an arm 19 capable of movement longitudinally of the shaft. The hub of the arm is provided with a cam slot 20 which is engaged by a pin on the frame 18, so that when the frame is swung horizontally, the arm will be raised or lowered according to the direction of movement of the frame.

The frame 18 is provided with a pulley 21 to which is attached a belt 22, one end of which passes over a guide pulley and carries a weight 23. The other end of the belt is secured to the end of a lever 24 which is pivoted at 25 to the frame 2. The lever 24 car-

ries an anti-friction roller 26 which is held in engagement with the cam 12 by means of the weight 23.

When the frame 18 is in the position shown in Fig. 2, the weight 23 on the end of the belt 22 and located below the level of the table, will tend to rotate the shaft and swing the free end of the frame toward the observer. As the frame is so swung, a roller 10 carried thereby and engaging the slot 20 in the hub of the arm 19 will depress the arm. When the arm is swung back to the position shown in Fig. 2 by the engagement of the cam 13 with a lever 24 which is attached to the pulley 21 by one end of the belt 22, the arm 19 will be raised to permit the lower member of the frame to pass under it.

Extending forward from the arm 15 are two extensions 27, 27, and extending downwardly from each extension to the table is a standard 28, and slidably carried on the standard is a bed piece 29. Engaging a pin in the bed piece is the slotted end of a lever 30. The lever is pivoted at 31 to the main frame, and its short arm carries a roller 32 which is engaged by the cam 12. Normally the bed piece is in the position shown in dotted lines in Fig. 2. When the cam 14 is rotated in the direction of the arrow the said cam engages a roller 32 and the short end of the lever 30. This raises the long end of the lever and with it the bed piece 29, and brings the article carried thereon in contact with the underside of the frame 18 and when the latter is removed the arm 19 will be lowered to the top of the article as will be hereinafter described.

Carried on the forward end of the bed piece 29 is an anvil 33. The anvil is provided with a removable face piece 34, having a boss 35. Mounted on one side of the anvil is a slide 36, see Fig. 3 having a bent over extremity 37 which engages the top surface of the article to be acted upon by the machine and retains it in place. The slide is held with the part 37 in engagement with the face piece 34 by means of a spring 38. The lower end of the slide extends below the anvil to such a distance that when the anvil is lowered the end of the slide will come in contact with the table before the anvil reaches the lowest extent of its travel, and the bent over portion 37 will be raised above and out of contact with the article so that the latter will be released.

Before the article is removed from its position and after the decalcomania has been caused to adhere to it by the pressure exerted by the bed piece 29 the paper which carried the decalcomania must be removed. This is accomplished by the following instrumentalities.

Pivoted to the bed piece is an arm 38^a. This arm is provided with a lever 39 which is connected by means of a pitman 40 with a

crank 41 on a shaft 42. Carried by the shaft 42 is a spur pinion 43 which meshes with a vertical rack 44 mounted on the table. As the table is lowered, as before described, the pinion 43 will be rotated by its engagement with the stationary rack 44. This will cause the end of the crank arm 41 to rise and through the pitman 40 move the lever 39 to the right. This will tilt the arm 38^a upward toward the bed piece 29. Hinged to the extremity of the arm 38^a is an arm 45 rigidly secured to a shaft 46. One end of the shaft 46 is formed with a crank 47, see Figs. 1, 2 and 3. A spring 48 engages the under side of the arm 45 and holds it in position. A double face cam 49 is carried by the bed piece 29. When the arm 38^a is swung upward the crank 47 will engage the lower face of the cam 49 and the arm 45 will be swung upward relatively to the arm 38^a. A spring 50 will prevent the arm being swung upward too far. When the crank passes the upper end of the cam 49, it will be swung outward by the weight of the arm 45 and the pressure of the spring 50, and on the downward movement of the arm 38^a the engagement of the crank with outer side or back of the cam 49 will tilt the crank 47 in the opposite direction and the arm 45 will be swung downward relatively to the arm 38^a. The free extremity of the arm 45 carries a block of rubber or other suitable material. When the crank 47 reaches the upper extremity of the cam 49 the arm 38^a will have been swung toward the bed plate and the free extremity of the arm carrying the rubber block will be over the anvil 35 but out of contact therewith. As the crank 47 is released from the cam by the continued downward movement of the same the arm 45 will be moved downward by the spring 50 and the rubber block on the arm will rest on the paper to which the decalcomania was formerly attached. When the upward movement of the bed piece takes place the pinion 43 will be rotated in the opposite direction. This will move the arm toward the position shown in Fig. 3, but before this position has been reached the rubber block will have been dragged from the upper side of the article and will draw the paper with it.

Carried on the end of the arm 19 is a moisture box 51. The bottom of the box 51 is open but a plate 52 carried by the bed piece 29 extends across the open bottom and is provided with an opening 53 of the same size as that of the decalcomania to be used. The opening is covered by a screen of gauze to permit the free escape of the moisture. This screen is extremely thin and is indicated by the lower line extending across the opening 53.

At one side of the bed piece is secured one end of a flexible table 54. This table is made flexible so that the end secured to the bed

piece may follow the movements of the latter. The free end of the table is provided with a spring which may be attached to any stationary object such as the floor or a part 5 of the main frame 1 of the machine.

Located at one side of the main frame 1 is a water tank 55. A pipe 56 extends from near the bottom of the tank to the moisture box 51. A pipe 57 from a source of compressed air enters the top of the tank. In 10 the pipe 56 is a valve 58 which is actuated to open and permit the air to enter the tank by means of the cam 14. The valve is an ordinary check valve which is held in closed 15 position by a spring and with its stem projecting through the casing. The cam 14 as shown in Fig. 2 is a segment carried on the shaft 11 and when, during the rotation of the shaft, it engages the stem, the valve will 20 be opened.

The operation of my improved device will be described in connection with the diagram shown in Fig. 5, and is as follows.

The machine being at rest, the frame 18 will be in the position shown in Fig. 3, and the bed piece 29 will be in the position shown in dotted lines in Fig. 2, by reason of the weight 23 pulling on the belt 22. The cams 12, 13 and 14 will be in the positions shown 25 in Fig. 5. The operator sitting in front of the table, that is the part farthest removed from the drive shaft 31, will turn an electric current into the coil of high resistance wire 18^a on the frame 18, place the article to be 30 marked on the anvil, the end of the article will be pushed under the turned over end 37 of the slide 36 which has been raised by contact of the opposite end of the slide with the floor, and place a decalcomania face down 35 on the article. If the article be of considerable length as a stocking or a necktie, it is laid on the table 54 with the part to be imprinted resting on the anvil and the decalcomania is placed on the part which rests on 40 the anvil, as shown in Figs. 2 and 3. When 45 the lower arm of the frame has become heated the operator will move the lever 8 to the right, and the drive wheel 4 will be clutched to the shaft, thereby starting the 50 machine and the cams 12, 13 and 14 will be revolved in the anti-clockwise direction.

As soon as the shaft starts, the face of the cam 13 will engage the roller 26 and move 55 the lever 24 to the right in Fig. 2, the latter being normally in the position shown in dotted lines in Fig. 2, and the frame 18 will start to move over toward the anvil 33. Directly after the cam face engages the roller 26, the face of the cam 12 will engage the 60 roller 31, the short end of the lever 30 will be depressed, carrying the bed piece, and with it the article to be marked and the decalcomania. When the bed starts to rise, the end of the slide will be pulled down on 65 the article by the spring on the slide. The

bed will rise until the roller 32 is at the point h. At the same time, the roller 26 has reached the point e on the cam 26, and the article and decalcomania are pressed and heated between the frame 18 and the anvil. 70 When the point i reaches the roller 32, the bed is lowered slightly and the point f on the cam 13 having left the roller 26, the weight 23 will swing the frame 18 to the position shown in Fig. 3, at the same time 75 lowering the arm 19 into contact with the anvil by reason of the engagement of the pin with the slot 20. While the arm is being lowered, the cam 14 comes into contact with the stem of the valve 58, depresses it and 80 opens the valve. The compressed air enters the tank 55, forces water in the form of spray in the moisture box 51, and through the screen in the plate 51, thereby moistening the back of the hot decalcomania and loosening it from the paper. The point n on the cam 12 has by this time reached the roller 32, and the short end of the lever 30 is 85 raised and the bed piece 29 is lowered to the position shown in dotted lines in Fig. 2. 90

As the bed piece is descending, the pinion 43 engaging the rack 44 will be rotated, swinging the crank 41, pitman 40 and lever 39, tilting the arm 38^a upward. The crank 47 will engage the lower face of the cam 49, 95 and raise the arm 45. When the arm reaches its upward limit the crank 47 will pass from the control of the lower face of the cam 49, and the block of rubber on the arm 45 will descend and rest upon the back of the paper 100 to which the decalcomania was attached. The continued movement of the pinion will swing the arm 38^a back to its initial position, and the crank engaging the top face of the cam 49 will depress the arm and hold it in 105 engagement with the backing while the arm 38 is being lowered, thereby scraping the backing from the transfer. By this time, the bed has reached the lowermost limit of its travel, the end of the slide 36 has come into 110 contact with the table, and released the article, and the machine is in position to resume its cycle of operation.

In accordance with the provisions of the patent statutes, I have described the principle of my invention together with the apparatus, which I now consider to represent the best embodiment thereof, but I desire to have it understood that the apparatus shown is merely illustrative, and that the invention 115 can be carried out in other ways without departing from the spirit of my invention.

Having now described my invention, what I claim as new and desire to secure by Letters Patent of the United States, is as follows:

1. A machine for transferring decalcomanias to separate articles, having means for supporting the article with a decalcomania in engagement therewith, means for 120

simultaneously applying heat and pressure to the article and decalcomania, and means for simultaneously applying moisture to the article and decalcomania.

- 5 2. A machine for transferring decalcomanias to separate articles, having means for supporting the article with a decalcomania in engagement therewith, means for simultaneously applying heat and pressure to the article and decalcomania, means for simultaneously applying moisture to the article and decalcomania, and means for removing the backing from the decalcomania.
- 10 3. In a machine for applying decalcomanias to separate articles, the combination with an anvil for supporting the article with a decalcomania resting thereon, a heater and a moistener, of means for bringing the article and decalcomania into contact with the heater, means for removing the heater from contact with the article and decalcomania, and means for bringing the heated article and decalcomania into contact with the moistener.
- 15 4. In a machine for applying decalcomanias to separate articles, the combination with an anvil for supporting the article with a decalcomania resting thereon, a heater and a moistener, of means for bringing the article and decalcomania into contact with the moistener.
- 20 5. In a machine for applying decalcomanias to separate articles, the combination with an anvil for supporting the article with a decalcomania resting thereon, a heater and a moistener, of means for bringing the article and decalcomania into contact with the heater, means for removing the heater from contact with the article and decalcomania, and means for bringing the heated article and decalcomania into contact with the moistener.
- 25 6. In a machine for applying decalcomanias to separate articles, the combination with an anvil for supporting the article with a decalcomania resting thereon, a heater and a moistener, of means for bringing the article and decalcomania into contact with the heater, means for removing the heater from contact with the article and decalcomania, means for bringing the heated article and decalcomania into contact with the moistener, and a wiper for removing the backing from the decalcomania.
- 30 7. In a machine for applying decalcomanias to separate articles, the combination with an anvil for supporting the article with a decalcomania resting thereon, a heater and a moistener, of means for bringing the article and decalcomania into contact with the heater, means for removing the heater from contact with the article and decalcomania, means for bringing the heated article and decalcomania into contact with the moistener, and a wiper for removing the backing from the decalcomania.
- 35 8. In a machine for applying decalcomanias to separate articles, the combination with an anvil for supporting the article with a decalcomania resting thereon, a heater and a moistener, of means for bringing the article and decalcomania into contact with the heater, means for removing the heater from contact with the article and decalcomania, means for bringing the heated article and decalcomania into contact with the moistener, and a wiper for removing the backing from the decalcomania.
- 40 9. In a machine for applying decalcomanias to separate articles, the combination with an anvil for supporting the article with a decalcomania resting thereon, an electric heater and a moistener, of means

for bringing the article and decalcomania into contact with the heater, means for removing the heater from contact with the article and decalcomania, and means for bringing the heated article and decalcomania into contact with the moistener.

10 6. In a machine for applying decalcomanias to separate articles, the combination with an anvil for supporting the article with a decalcomania resting thereon, an electric heater and a moistener, of means for bringing the article and decalcomania into contact with the heater, means for removing the heater from contact with the article and decalcomania, means for bringing the heated article and decalcomania into contact with the moistener, and a wiper for removing the backing from the decalcomania.

15 7. In a machine for applying decalcomanias to separate articles, the combination with an anvil for supporting the article with a decalcomania resting thereon, a heater and a moistener, of means for bringing the article and decalcomania into contact with the heater, means for releasing the contact between the article and the heater, means for swinging the heater from the path of the article, means for bringing the article and decalcomania into contact with the moistener, means for injecting water into the moistener, means for removing the article and decalcomania from contact with the moistener, and a wiper for removing the backing from the article.

This specification signed and witnessed this 10th day of May, 1915.
